(57) **CLAIM**

The ornamental design for a game ball, as shown and described.

DESCRIPTION

FIG. 1 is a perspective game ball according to the present application.

FIG. 2 is a front view of the game ball.

FIG. 3 is a back view of the game ball; and,

FIG. 4 is a top plan view of the game ball.

The broken lines in the drawings depict portions of the game ball and form no part of the claimed design.
